UNITED STATES PATENT OFFICE.

LOUIS HELMER, OF NEW YORK, N. Y.

REFRIGERATING APPARATUS.

Application filed May 27, 1924. Serial No. 716,141.

This invention relates to a refrigerator, and particularly to a refrigerator adapted for household use, wherein the cooling is accomplished by the expansion of a liquid gas 5 in cooling coils.

One object of the present invention is to provide an economical fluid-operated impelling means for the gas compressor, and in so 10 constructing the refrigerator that the exhaust fluid from the impelling means will act to condense the compressed gas.

With this and other objects in view, as will appear as the description progresses, my invention resides in the combination and arrangement of parts set forth in and falling 15 within the scope of the appended claims.

In the drawings

Figure 1 is a front elevation of a refrigerator constructed in accordance with my invention; and

Figure 2 is a section through the back of the refrigerator, showing the arrangement of the condenser coils and compressing apparatus.

Referring to the particular embodiment of the invention shown, which is chosen merely for the sake of illustrating the invention, and not with any intention of limiting the invention to the details thereof, the refrigerating 20 casing 1 is provided with the usual food receiving chambers 2, and with a refrigerating coil 3. A gas condenser is arranged adjacent this coil 3, and preferably in the wall of the casing. This condenser may be of any desirable type, but I have illustrated one which 25 includes a series 4 of double tubes, wherein the gas passes through one set of tubes from a header 5 to a lower header 6, and wherein the cooling water passes through to the other 30 set of tubes. The lower header 6 of the condenser is connected to the refrigerating coil 3 by a conduit 7. A conduit 8 connects the coil 3 to a rotary gas compressor 9, which latter is connected to the upper header 5 by a 35 conduit 10. The numeral 16 represents the conventional expansion valve located in the conduit 7 leading from the condenser to the expansion coil 3.

It will be seen that the liquid gas passing 40 from the lower header 6 through the conduit 7 and expansion valve 16 expands upon reaching the cooling coil 3, and the thus expanded gas passes through the conduit 8 to the rotary compressor 9, where it is compressed and from which it is fed to the 45 condenser tubes.

In order that the rotary compressor may be actuated to compress the gas which it receives from the cooling coils 3, and in order that the compressed gas may be condensed, I 50 have provided a fluid-operated motor 11, which is mounted, preferably, adjacent the rotary compressor 9, and is provided with a supply pipe 12, the rate of flow through which may be controlled by a valve 13. The 55 motor shaft 14 is connected to the rotor of the compressor 9.

This fluid-operated motor 11 is connected with the water tubes of the condenser, so that the fluid, after actuating the motor, is 60 exhausted into the fluid receiving tubes of the condenser. From the lower ends of the water receiving tubes 4, an outlet 15 extends. It will thus be seen that as the expanded gas 65 passes from the cooling coils 3 to the compressor 9, the actuation of this latter by the motor 11 will cause the compression of the gas and its feeding into the gas receiving tubes of the condenser.

The passing of the exhaust fluid from the 70 motor 11 acts as a cooling agent for the thus compressed gas, and effects liquefaction of the gas in the condenser, so that when the gas reaches the lower header 6 it is in a 75 liquid state, and ready to again be fed through the conduit 7 to the cooling coils 3. As best shown in Figure 2, the condenser is located in the back wall of the refrigerator and substantially covers the entire area 80 thereof so that the maximum surface of the condenser is exposed to the cooling action of the exhaust from the motor and, at the same time, a minimum amount of space is taken up thereby.

From the foregoing description it will be 85 seen that I have provided a refrigerating system which depends upon the expansion of liquid gas and one wherein the cycle of expansion and liquefaction is effected with the greatest possible economy. This economy 90 is effected by using the same fluid which actuates the gas compressing unit as a cooling or condensing medium for the gas after it is compressed, and by exhausting the fluid 95 from the actuating motor to the cooling tubes by gravity.

It will further be seen that the arrangement and construction of the apparatus is such that it may be connected directly to the usual water supply from a tank or a 100 city system, and will operate at the pressures usually encountered in such systems. How-

ever, the pressure and flow of the cooling fluid through the condenser tubes may be controlled at the will of the operator.

What I claim is:

- 5 In a refrigerator, a cyclic gas cooling system comprising an expansion coil located in one compartment, a condenser located in the wall of the refrigerator and substantially covering the entire area thereof, a compressor and fluid actuated motor therefor

located above the condenser in a compartment of the refrigerator, and means connecting the exhaust of said fluid actuated motor to the condenser whereby the exhaust fluid acts to liquefy the condensed gas.

15

In testimony whereof, I have signed my name to this specification this 19th day of May, 1924.

LOUIS HELMER.
